CLAIM

The ornamental design for a trim extrusion set, as shown and described.

DESCRIPTION

FIG. 1 is an isometric view of a trim extrusion set according to the present disclosure.

FIG. 2 is an exploded view of the trim extrusion set of FIG. 1

FIG. 3 is a left side view of the trim extrusion set of FIG. 1. The right side view of the trim extrusion set of FIG. 1 is a mirror image of the left side view.

FIG. 4 is a rear view of the trim extrusion set of FIG. 1.

FIG. 5 is a front view of the trim extrusion set of FIG. 1.

FIG. 6 is a top view of the trim extrusion set of FIG. 1; and, FIG. 7 is a bottom view of the trim extrusion set of FIG. 1. The trim extrusion set is shown with two parallel dash-dot break lines that represent the bounds of the claim. The appearance of any portion of the trim extrusion set between the break lines forms no part of the claimed design.
